UNITED STATES PATENT OFFICE

MICHELL L. FYKSE, OF SOUTH MILWAUKEE, WISCONSIN, ASSIGNOR TO BUCYRUS-ERIE COMPANY, OF SOUTH MILWAUKEE, WISCONSIN, A CORPORATION OF DELAWARE

BACK DIGGING SHOVEL

Original application filed July 27, 1928, Serial No. 295,661. Divided and this application filed May 3, 1929. Serial No. 360,089.

My invention relates to new and useful improvements in back digging shovels.

This application is a divisional of my co-pending application, Serial No. 295,661, filed July 27, 1928.

Back digging shovels are well known in the excavating art. They are characterized by a dipper mounted on the lower end of a handle, which is pivoted intermediate its ends on the outer end of the boom, the inner end of the boom being pivoted to the frame of the machine. The shovel faces toward the machine. On the main frame of the machine is a two-drum winch, from which one rope, associated with the dipper, tends to drag the dipper toward the machine. The other rope of the winch is associated with the upper end of the dipper handle and tends both to raise the boom and to cause the dipper to move away from the machine.

The principal object of my invention is to provide a novel swivel for the dipper handle. Further objects and advantages of my invention will be readily evident, as the description progresses.

The invention consists in the novel parts, and in the combinations and arrangements thereof, which are defined in the appended claims; and of which one embodiment is exemplified in the accompanying drawings, which are hereinafter particularly described and explained.

Throughout the description, the same reference number is applied to the same member or to similar members.

Figure 1 is a side elevation of a power shovel embodying my invention.

Figure 2 is a rear elevation of the dipper handle and associated parts, viewed from line 2-2 of Figure 1.

Figure 3 is a partial elevation of the dipper handle, similar to Figure 2, but showing an alternative form.

Referring to the drawings, it will be seen that 5 is the main base of the power shovel, supporting the boom 6, the A-frame 7, and the main winch 8.

The main winch 8 includes two hoist drums 9 and 10, actuatable by any convenient power source (not shown).

On the outer end of boom 6 is a hinge pin 11, which serves as a horizontal pivot for the handle 12. Hinged to the boom by the hinge pin 11 is a swivel piece 13 provided with a swivel axle 14 which extends through a bushed hole in the handle 12.

The swiveling of the handle is limited by two arms 15, and associated devices shown in detail in Figure 2. To each of these arms, at 16, is pivoted a bolt 17, which is free to reciprocate in hole 18 in the handle 12. Nuts 19 near the top of the bolt 17 bear against a plate 20, which in turn bears against a compression spring 21, which in turn bears against a block 22, which in turn bears against the handle 12. The spring 21 is surrounded and protected by a cylinder 23.

The two springs tend to limit the swiveling of the handle and to restore it to its normal vertical position.

In the variant of this device shown in Figure 3, the two arms 15 bump against wooden bumper blocks 24 projecting from the ends of cylinder 23', which are secured to the handle 12 by bolts 17' and nuts 25.

A spring bumper 26 is provided on the top of the outer end of the boom 6 to contact with bumper plate 27 of the handle 12 whenever the handle is in its most extended position.

On the upper end of the handle are two hoist sheaves 28, and on a bracket 29 in the lower end of the handle is a padlock sheave 30.

A digging dipper 31 is held by the lower end of the handle 12 and by a brace 32.

A rope 37 passes from an anchorage 34 on the boom 6, around the padlock sheave 30, thence through the boom and between two guide sheaves 38 on the A-frame 7, to the drum 9 of the main winch 8. A rope 39 is anchored in a rope socket 40 which is pivoted to the apex of the A-frame 7. This rope then passes around one of the hoist sheaves 28, thence around one of the sheaves 41 at the apex of the A-frame, thence around the other hoist sheave 28, thence around the other sheave 41 at the apex of the A-frame, and thence to the drum 10 of the main winch 8.

Digging is accomplished by pulling in on rope 37, the exact height of digging being va-

ried by slightly pulling in or paying out rope 39. When the full dipper 31 has been pulled as near as possible to the boom 6, it is maintained in that position by further pulling in 5 on the rope 37, as hoisting is accomplished by rope 39. When hoisted to the desired spot, dumping is effected by pulling in on rope 39 and simultaneously paying out rope 37.

- 10 Although swivels for dipper handles of back digging shovels are old in the art, and have even been arranged so as to swing in a plane rather than in a cone, and furthermore have even been provided with stops to limit 15 the swinging from side to side, these stops have never been sufficiently wide spaced nor sufficiently resilient to eliminate jar and breakage. My invention eliminates these difficulties.
- 20 Having now described and illustrated one form of my invention, I wish it to be understood that my invention is not to be limited to the specific form or arrangement of parts hereinbefore described, except insofar as such 25 limitations are specified in the appended claims.

I claim:

1. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 30 its ends to said member, for swinging about said member laterally in a plane; a digging dipper mounted on the lower end of said handle; means extending substantially widely beyond the width of said handle for limiting this lateral swinging; and means for swinging said boom and said handle, to perform the digging operations.
2. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 45 its ends to said member, for swinging about said member laterally in a plane; a digging dipper mounted on the lower end of said handle; means for limiting this lateral swinging and for positively returning the handle to the same vertical plane with the boom; and means for swinging said boom and said handle, to perform the digging operations.
3. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 50 its ends to said member, for swinging about said member laterally in a plane; a digging dipper mounted on the lower end of said handle; spring means for limiting this lateral swinging and for returning the handle to the same vertical plane with the boom; said spring means consisting in two springs carried by the handle and bearing respectively against lateral projections from the pivoted member; and means for swinging said boom and said handle, to perform the digging operations.
4. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 55 its ends to said member, for swinging about said member laterally in a plane; a digging dipper mounted on the lower end of said handle; spring means for limiting this lateral swinging and for positively returning the handle to the same vertical plane with the boom; and means for swinging said boom and said handle, to perform the digging operations.
5. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 60 its ends to said member, for swinging about said member laterally in a plane; a digging dipper mounted on the lower end of said handle; means projecting laterally from both pivoted member and handle, for limiting this lateral swinging and for positively returning the handle to the same vertical plane with the boom; and means for swinging said boom and said handle, to perform the digging operations.
6. In a machine of the class described, the combination of: a main frame; a boom, pivoted at its lower end to the frame, for swinging in a vertical plane about its pivot; a member, pivoted to the outer end of the boom, for swinging in a vertical plane about its pivot; a dipper handle, pivoted intermediate 65 its ends to said member, for swinging about said member laterally in a plane; a digging dipper mounted on the lower end of said handle; spring means for limiting this lateral swinging and for returning the handle to the same vertical plane with the boom; said spring means consisting in two springs carried by the handle and bearing respectively against lateral projections from the pivoted member; and means for swinging said boom and said handle, to perform the digging operations.

In testimony whereof I affix my signature.

MITCHELL L. FYKSE. 1
